(57) **CLAIM**

The ornamental design for a tool box, as shown and
described.

DESCRIPTION

FIG. 1 is a perspective view of a tool box showing my new
design;

FIG. 2 is a front elevational view thereof;

FIG. 3 is a top plan view thereof;

FIG. 4 is a left side elevational view, the right side eleva-
tional view being a mirror image thereof; and,

FIG. 5 is a rear elevational view thereof.

The broken line portions of the disclosure are for illustrative
purposes only and form no part of the claimed design.
